UNITED STATES PATENT OFFICE

97,185

DESIGN FOR TEXTILE FABRIC

Curt Erwin Forstmann, Montclair, N. J.

Application September 4, 1935, Serial No. 58,431

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric em-

bodying the design of the present invention, the cloth depicted is of a single color.

The design comprises parallel rows of small elevated parallelograms composed of closely arranged irregular tufts, the background appearing between the parallelograms as parallel lines of depression, intersecting perpendicularly.

I claim:

The ornamental design for textile fabric as shown and described.

CURT ERWIN FORSTMANN.
